UNITED STATES PATENT OFFICE.

OLE CHRISTENSEN AND CHRISTIAN PETER SÖLBECK, OF COPENHAGEN, DENMARK.

COMBINED CHURN AND BUTTER-WORKER.

No. 882,745.

Specification of Letters Patent. Patented March 24, 1908.

Application filed September 18, 1907. Serial No. 393,536.

To all whom it may concern:

Be it known that we, OLE CHRISTENSEN, of Westerbrogade No. 36, Copenhagen, in the Kingdom of Denmark, manufacturer, and CHRISTIAN PETER SÖLBECK, of Istedgade No. 45, Copenhagen, in the Kingdom of Denmark, merchant, have invented certain new and useful Improvements in a Combined Churn and Butter-Worker; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of the present invention is a combined churn and butter worker, which is specially intended for minor dairy trade, eventually used as hand-churn.

It is characterized by the production of two different working-phases for each half revolution of the churn barrel. The eventually easily removable kneading device consists of three side by side lying rollers which work the butter in two alternating directions each corresponding to its half revolution of the barrel. The middle roller is fixed to the common shaft of the barrel and the kneading device, and during the churning the barrel and all the parts are coupled together in such a manner that they rotate with the angular velocity of the shaft while there is no reciprocal movement of the rollers. During the kneading, on the contrary, the barrel rotates slower, while the velocity of the shaft is constant with regard to the rollers, which are now turned mutually against each other.

A couple of alternative arrangements are shown in the accompanying drawing.

Figure 1 shows a vertical section on the line A—B in Fig. 2 through a machine with an oval barrel, Fig. 2 a horizontal section on the line C—D in Fig. 1, Fig. 3 is a vertical section on the line E—F in Fig. 4, through a machine with barrel formed container, which is revolved on a shaft parallel to the bottom, Fig. 4 is a horizontal section on the line G—H in Fig. 3, and Fig. 5 is the outside view of the barrel shown in Fig. 3.

In Figs. 1 and 2 the letter *a* indicates the oval churn barrel, *b*, *c* and *d* the three rollers which are placed between the supporting

part *e* and a central bottom plate *f*. The supporting part bears against the backwall *g* of the barrel and the bottom plate is let into a central opening in the front wall *h*. The parts *e* and *f* are supplied with a central hole or bearing for the shaft *i* which carries the roller *c* and with eccentrically placed bearings for the shafts *j* and *k* of the rollers *b* and *d*. The three bearings in the disk *f* are supplied with stuffing-boxes.

l is the foremost, and *m* the hindmost bearing of the machine in which (latter) the barrel is resting on the hollow pivot *n* through which the driving shaft *i* passes. The end of *i* is screw threaded, and carries a hand-wheel and a coupling device, which may be coupled to and from the pivot *n* by means of the hand-wheel. On the front of the machine a pinion *p* is fixed to the driving shaft *i* and corresponding pinions *q* & *r* to the shafts *j* & *k*. Further another pinion *s* is placed on the driving shaft *i* and on the shaft *j* is placed a revolving intermediate pinion *t* which gears partly with the pinion *s* and partly with the toothed rim *u* on the disk *f*.

v are drivers, *x* guide-plates for the butter and *z* doors which close the entrance-openings. When the machine has to be used for churning the driving shaft *i* is by means of the coupling arrangement *o* coupled to the pivot *n* carrying the barrel *g*, *a*, *h*. When the driving shaft *i* is turned by means of the hand-wheel shown or by a belt device all the parts *i. e.* the barrel and the kneading device will rotate with the angular velocity of the driving shaft, so that none of the pinions are in action.

When the machine has to be used as butter worker the coupling *o* is disconnected as shown in Fig. 2. The revolution of the driving shaft will then be transferred to the barrel with diminished velocity through the pinion *s*, the intermediate pinion *t* and the rim *u* while the roller *c* will keep the original velocity and the rollers *b* & *d* are revolved with the same velocity in relation to it by means of the pinions *p*, *q* & *r*. Meanwhile the kneading device as a whole rotates at the same slow speed as the barrel itself and during each half revolution the kneading process shown in Fig. 1 occurs, since mainly only the two rollers *b* & *c* or *d* & *c* are alternatively in action. When the coupling *o* is disconnected and the hand wheel removed, the

driving shaft and the kneading device may be bodily withdrawn from the front of the machine.

The arrangement shown in Figs. 3 to 5 differs from the now described arrangement in, that the barrel is shaped as an upright ordinary one, which is revolving on a horizontal shaft through the middle of the side walls and parallel with the bottoms of the barrel. Besides the kneading device is not directly removable, but the supporting piece *e* as shown in Fig. 4 is screwed to the wall of the barrel and the disk *f* is omitted, the stuffing-boxes of the shafts *i*, *j* and *k* being in the wall of the barrel itself. Instead of the hand-wheel and the coupling device *o* one to the driving shaft *i* fixed coupling branch *o'* which may be coupled in a certain position by means of one to the rim *u* or another suitable place fixed grip *n'*, might for instance be used. Further the central pinion *s* and the intermediate pinion *t* are discarded and replaced with the following arrangement. The pinion *q* is connected with a special pinion *t'* which gears in the rim *u* and thereby imparts the slow speed to the barrel during the kneading. The pinion *q* *t'* in this case acts as an intermediate pinion, it being the pinion *p* that takes the part of the pinion *s*. For the sake of easy cleaning one of the bottoms *y* may be removable as indicated in Fig. 3.

Having now particularly described and ascertained the nature of this said invention and in what manner the same is to be performed we declare that what we claim is:

1. In a combined churn and butter worker, the combination with a receptacle of a central roller therein, rollers at the sides of said central roller, a central shaft carrying said central roller and being in direct connection with the driving device, means for driving the side rollers from the central shaft and means for coupling and uncoupling the receptacle and said central shaft.

2. In a combined churn and butter worker,

the combination with a churn barrel of a central roller therein, rollers at the sides of said central roller, a central shaft carrying said central roller, a driving member in direct connection with the driving shaft and means for transmitting the movement of the central shaft to the churn barrel at a reduced speed.

3. In a combined churn and butter worker, the combination with a churn barrel, of a central roller and two side rollers with bearings in the churn barrel, a centrally arranged driving device, means for transmitting the movement to the side rollers, and means for transmitting the movement at two speeds to the churn barrel, said barrel not being circular in the plane of rotation.

4. In a combined churn and butter worker, the combination with a receptacle, of a central driving shaft mounted therein, a roller carried by the shaft, rollers at the sides of the central roller, gearing connecting the central and side rollers, and gearing connecting the driving shaft and receptacle.

5. In a combined churn and butter worker, the combination with a receptacle, of a central driving shaft extending through the receptacle, a roller carried by the shaft, lateral shafts mounted in journals fixed to one side of the receptacle and extending through the latter parallel with the driving shaft, rollers on the lateral shafts, gears connecting the driving and lateral shafts, a gear on the receptacle, gears connecting the latter gear with the driving shaft and a coupling device to connect the shaft and receptacle.

In testimony that we claim the foregoing as our invention, we have signed our names in presence of two subscribing witnesses.

OLE CHRISTENSEN.
CHRISTIAN PETER SÖLBECK.
